Term of patent 14 years

Int. Cl. D6—01

U.S. Cl. D6—30

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a front view of a first embodiment of my chair or similar article, incorporating my invention;

FIG. 2 is a side view thereof, the opposite side being similar to the side shown;

FIG. 3 is a rear view thereof;

FIG. 4 is a perspective view thereof;

FIG. 5 is a front view of a modified embodiment of my chair or similar article, incorporating my invention;

FIG. 6 is a side view thereof, the opposite side being similar to the side shown;

FIG. 7 is a rear view of the chair or similar article depicted in FIG. 5;

FIG. 8 is a perspective view thereof;

FIG. 9 is a front view of a further modified embodiment of my chair or similar article, incorporating my invention;

FIG. 10 is a side view thereof, the opposite side being similar to the side shown;

FIG. 11 is a rear view of the chair or similar article depicted in FIG. 9; and

FIG. 12 is a perspective view thereof.

I claim:

The ornamental design for a chair or similar article, as shown and described.
